UNITED STATES PATENT OFFICE

2,090,603

CONDENSATION PRODUCTS OF 2,3-HYDROXYNAPHTHOIC ACID

Wolfgang Winkelmüller, Leverkusen-Wiesdorf,
Germany, assignor to General Aniline Works,
Inc., New York, N. Y., a corporation of Dela-
ware

No Drawing. Application November 7, 1935,
Serial No. 48,777. In Germany November 14,
1934

4 Claims. (Cl. 260—32)

The present invention relates to condensation products of 2,3-hydroxynaphthoic acid bearing in the naphthalene nucleus substituents which do not cause solubility in water with anthranilic acid amide or its substitution products, more particularly it relates to compounds which may be represented by the following formula:

wherein the naphthalene nucleus bears substit-

potassium acetate or when introducing the compound into a sodium-chloride-aluminium-chloride melt. Most practically the ring closure is performed by heating and dissolving the substance sub III in aqueous caustic alkali lye. On cooling, the alkali metal salt of the new compound indicated above sub II which is difficultly soluble in excess alkali separates; it easily can be isolated, and with the aid of acids the free compound can be obtained. Or otherwise the free compound can be obtained by introducing carbon-dioxide into the hot alkaline solution whereby the free compound is precipitated.

It has already been known that the benzoyl- (and also the acetyl-) anthranilic acid amide having the formula:

yields the corresponding condensation product by splitting off water (see Körner, Journal für praktische Chemie, N. F. vol. 36, page 155); however, from this, the chemical behaviour of the 2,3-hydroxynaphthoyl-anthranilic acid amides could not be foreseen, it rather could be expected that the hydroxy group in *o*-position would influence the proceeding of the reaction. First of all it could not be expected that the new condensation products would have the valuable properties of the 2,3-hydroxynaphthoic acid arylamides and therefore would be important intermediate products for the manufacture of dyestuffs of good fastness properties.

The invention is illustrated by the following examples, without being limited thereto, the parts being by weight:

Example 1

40 21.8 parts of 6-methoxy-2,3-hydroxynaphthoic acid, 50 parts of toluene and 11.9 parts of thionylchloride are heated at 90-100° C. with the exclusion of moisture until a clear solution has 45 formed and the development of hydrochloric acid has ceased. The solution of the 6-methoxy-2,3-hydroxynaphthoic acid chloride obtained is added in portions while stirring to a warm solution of 13.6 parts of anthranilic acid amide in 300 parts of toluene, and the reaction mixture is 50 refluxed until hydrochloric acid does no longer escape. Thereby the 6-methoxy-2,3-hydroxynaphthoyl anthranilic acid amide separates in form of a greenish yellow somewhat resinous 55 intermediate (after recrystallizing from nitrobenzene decomposing at 232° C.). By dissolving the reaction product in an aqueous caustic soda lye of 4% and heating the ring closure is performed and the condensation product having the 60 following formula:

70 is precipitated as a greyish green powder by introducing carbon dioxide (point of decomposition above 300° C.).

In an analogous manner there have been prepared the condensation products from anthranilic acid amide and 7-methoxy-2,3-hydroxy-

naphthoic acid (point of decomposition above 300° C.); 6-methyl-2,3-hydroxynaphthoic acid (point of decomposition above 300° C.); 6-bromo-2,3-hydroxynaphthoic acid (point of decomposition above 300° C.), found by analysis 21.2% of bromine, calculated 21.8% of bromine; 7-chloro-2,3-hydroxynaphthoic acid (point of decomposition above 360° C.), found by analysis 8.5% of nitrogen, 11.2% of chlorine, calculated 8.7% of nitrogen, 11.0% of chlorine. Further in an analogous manner there have been prepared the condensation products from 2-amino-4-methoxybenzamide and 6-methoxy-2,3-hydroxynaphthoic acid (point of decomposition above 300° C.); from 4-methyl-2-aminobenzamide and 7-methoxy-2,3-hydroxynaphthoic acid (point of decomposition above 300° C.).

Example 2

20 Into a suspension of 23.2 parts of 8-nitro-2,3-hydroxynaphthoic acid and 13.6 parts of anthranilic acid amide in about 250 parts of toluene there are dropped while stirring 10 parts of phosphorus trichloride dissolved in 30 parts of toluene. The reaction mass is heated to boiling, while further stirring until the development of hydrochloric acid has ceased, whereby the reaction product having the following formula:

35 separates in form of a yellowish brown fine precipitate. After cooling the precipitate is filtered with suction, washed with a little quantity of toluene and dried. By recrystallizing from pyridine or nitrobenzene it can be purified and is then obtained in form of a yellow crystalline powder, having a point of decomposition above 310° C.

I claim:

1. 2,3-hydroxynaphthoic acid derivatives of 50 the formula:

60 wherein the naphthalene nucleus bears at least one substituent selected from the group consisting of alkyl, alkoxy, halogen and the nitro group, and wherein

70 stands for a member selected from the group consisting of a benzene nucleus and an alkyl-, alkoxy-, halogen- and nitro-substituted benzene nucleus, being generally yellowish crystalline substances soluble in alkalies and being valuable intermediate products for the manufacture of dyestuffs.

2. The compound of the following formula:

being a yellowish crystalline substance soluble in alkalies and being a valuable intermediate product for the manufacture of dyestuffs.

4. 2,3-hydroxynaphthoic acid derivatives of the formula:

being a yellowish crystalline substance soluble in alkalies and being a valuable intermediate product for the manufacture of dyestuffs.

15 3. The compound of the following formula:

wherein the naphthalene nucleus bears at least one substituent selected from the group consisting of alkyl, alkoxy, halogen and the nitro group, and wherein R stands for a monocyclic arylene radical free from water solubilizing groups, being generally yellowish crystalline substances soluble in alkalies and being valuable intermediate products for the manufacture of dyestuffs.

WOLFGANG WINKELMÜLLER. 25
